UNITED STATES PATENT OFFICE.

HERMAN BESSER AND JESSE H. BESSER, OF ALPENA, MICHIGAN.

TAMPING MACHINE.

Application filed November 28, 1923. Serial No. 677,413.

To all whom it may concern:

Be it known that we, HERMAN BESSER and JESSE H. BESSER, residents of the city of Alpena, in the county of Alpena and State 5 of Michigan, and citizens of the United States, have invented certain new and useful Improvements in Tamping Machines, of which the following is a specification.

Our invention relates to new and useful 10 improvements in tamping machines for use in mixing concrete material, packing material in molds, in ore crushing and in kindred uses.

It is a special object of our machine to 15 provide means for tamping material by the weight of a battery of tamping units which are permitted to fall together after release from the actuating means utilized to raise them intermittently against the force of 20 gravity.

It is a further object of our invention to utilize the force of a rotating member to lift the battery of tampers and permit their falling together. Attempts have heretofore 25 been made to actuate tampers in sets, and by the force of gravity too, but either the tampers have been lifted separately, or means other than a revolving element has been used to lift the set together. We find 30 there is a distinct advantage in the descent of an entire battery at one time, resulting from their concerted action upon the material to be crushed or molded, and also due to the fact that a rotating element is far 35 more advantageous than are other forms of actuating mechanism for intermittently lifting weights, as, for example, endless belts.

It is a further object of our improved construction to provide, in combination with a 40 series of reciprocating tampers in concerted action, a readily movable manually-operable or power-operated lever element to effectively obstruct, though temporarily, the falling movement of the tampers, and if 45 desired, secure them in such upper position indefinitely, while being capable of removal from such locked position by a thrust of the lever in the opposite direction.

It is an especially advantageous feature 50 of our improved mechanism that the said cut-out lever mechanism may be actuated to tend to obstruct said passage way of the tampers, even when the latter are not in the uppermost position, without injury of 55 parts in the least, since the lever mechanism will harmlessly press against the tampers

in their vertical movement until opportunity is afforded said mechanism to crowd under the supporting means for the tampers to lock the latter in their extreme upper 60 position. When the lever is released, the tamper lifting or actuating mechanism will again become active as before.

A still further object of our invention is the provision of tamper locking means 65 which by manual actuation, not only locks the tampers in inoperative position, but also lifts the whole series to a height far out of reach of any rotating arms or bars used for mechanical actuation of the tampers, 70 thus avoiding accidents and injury to actuating machinery, even when the operation of the latter is continuous.

With these and other objects of our invention in view, as will appear as the description proceeds, the same consists in the novel combination and arrangement of parts hereinafter fully described, recited in the appended claims and illustrated in the accompanying drawings, in which— 75

Figure 1 is a front elevation of our machine;

Figure 2 is a side elevation showing the tamper bars in extreme upper position and locked there; 85

Figure 3 is a similar view showing the tampers approaching the uppermost position, and the locking mechanism just beginning to become effective, and

Figure 4 is a similar view showing the locking mechanism in inoperative position, 90 and the other parts in normal working operation.

In the drawings in which like reference characters designate corresponding parts 95 throughout the several views, numeral 10 designates the main shaft mounted transverse of the frame comprising vertical pieces 12 and cross bars 13. Fixed to said shaft is the belt pulley 11 by which power 100 is conveyed to the latter. It may be mounted on either end of the shaft, and is driven continuously while the machine is running. The tamper bars 15 are suitably guided in the frame for vertical reciprocation 105 therein, and may have suitable feet 54 whose character depends upon the kind of work to be done. Each tamper bar is provided with a cross actuating block 31 secured thereto in a suitable manner, as by 110 riveting at 32. These blocks have parallel upper and lower edges, the upper being

shorter than the lower. The end edges have parallel lower portions substantially vertical when the machine is set up, but upper portions 37 inclined toward the tamper bar. 5 One end of each cross block extends rearwardly and projects farther from its support than the forward end, to provide convenient edge at 33 for raising the tamper. Mounted inside the frame and upon the 10 main shaft are two eccentric castings 16 spaced apart sufficiently to receive the tampers within their two planes. These castings are keyed to the shaft on which they are carried, and comprise one arc 17 as a counterbalance, and opposite it a projecting lip 18 having an aperture therethrough on the cord of its arc, and a pivot portion on which a tongue member 22 having a ring portion 21 is pivoted at 20, in 15 the plane of the casting 16, so that the tongue may rock toward and from the flattened edge 19 of the lip 18. The latter part is also apertured on a cord so that, when the tongue is swung into parallelism with 20 the lip, the apertures will be in alignment. A bolt 23 having an angled head 28 is threaded loosely through the two apertures, a coiled compression spring 24 encompassing the bolt between the lip and tongue, 25 and another similar spring 25 mounted on the bolt below the lip. A washer 26 is pushed on the bolt over the end of the spring 25, and a key 27 inserted in the end of the bolt to lock the parts together. 30 The above-described structure is utilized to render a yielding thrust of the tamper bars in raising them, as well as a yielding reaction on release, and the manner of accomplishing this is as follows: A common 35 transverse bar 29 for actuating all the tampers is carried yieldingly by the said castings 16, but not rigidly. The ends of this bar 29 are passed through cross apertures in the said tongues 22 just rearwardly 40 of the bolt 23, and secured fixedly therein. As therefore said bar 29 encounters unusually heavy load or resistance, springs 24 will be compressed and yield slightly to avoid too sudden jar. On the other hand, 45 when the rotation of shaft 10 has continued to the point where the bar 29 has slipped out from under the edge 33 of the block 31, the force of spring 24 will react to swing shoulders 22 and bar 29 away from lips 18, but springs 25 are thereby compressed 50 to avoid undue vibration of parts. For temporarily locking the entire set of 55 tampers in raised position, when for any reason the tamping operation is not desired for an interval, we have provided a pivoted locking mechanism which will now be described. Vertical bars 14 are provided at 60 sides of the frame which are parallel to the tamper bars and slightly forward of the latter. On these bars 14 are pivoted for

rocking motion therein lever members 42 having offset stub shafts 40 projecting through these bars 14 and having keys 58 securing them in place. Integral with levers 42 are ears 59, and said stub shafts, 70 the hollow lug 41 being at an angle to the pivot ears. Transverse of the machine is a rock shaft 38 which is splined to 42, so that actuation of one of the levers 42 by the manual lever 39 will also actuate the 75 part 42 at the opposite side of the machine. Within the hollow lug 41 an arm 43 is pivoted on the bar 38 and limited in its rocking movement by the enlarged angular opening in the said lug, and rocking on the same 80 bar is a pair of arms 44 and 64 bearing at the extremity of 64 and midway of 44, a cross bar 51 which may engage the forward ends of the blocks 31 beneath the lower edges 34 thereof. The arm 44 is 85 extended to form a projection 48 having a pin 49 to which an extension spring 53 is attached and fixed at its opposite end to the end of the arm 43. At a point just forward of the bar 51 of the arm 44 is an 90 ear having a pin 47 to which the extension spring 53 is connected at one end, and the other end connected to a pin 52 on the frame piece 12. The force of the spring 53 is therefore exerted to swing the arm 44, and with it arm 64, on its fulcrum 38, rearwardly against the tampers until the bar 51 contacts their forward edges. If at the time the bar 51 reaches the tampers, the 95 blocks 31 are beneath the bar, the next upward stroke of the tampers will cause the inclined edges 37 to contact the bar 51 and swing the same forwardly until the blocks have passed it, when the bar will swing under the blocks by the force of said spring, 100 and prevent falling of the tampers when they are released by the bar 29. 105 The two springs 50 and 53 have equal strength, but it will be seen that the latter acts at a mechanical disadvantage with respect to the spring 50, since 53 is attached to arm 44 nearer its fulcrum, and therefore its force will be overcome by spring 50 when arm 43 is rocked on its pivot 38. The latter condition arises when force is manually applied to the lever 39 which, being integral with 41, will rock the latter forward on its pivot 40, when 39 is forced backward. It will thus be seen that when arm 39 is moved forward, 43 moves rearwardly and upwardly to release spring 50, since the arm 43 is then released by 41, thus permitting spring 53 to draw the arms 44, 64, and the bar 51 carried thereby, rearwardly against the tampers, as above described. A sleeve 110 45 is made integral with arms 44 and 64 to receive the end of the rod or bar 51, and a sleeve 46 is also secured to the lower end of 44 and of 64 for receiving the shaft 38 therein and strengthening the opening of 115 120 125 130

these arms which are to rock upon shaft 38. Lug 41 is provided with a forward opening to permit 43 to be released, but has a positive rear wall 60 by which forward movement of 5 41 carries 43 with it.

5 Lever 39 is bent outwardly and downwardly, as shown in Fig. 1, and a bar 56 is secured to the frame and provided with notches 57 to receive therein the lever at 10 opposite positions of its swing, to provide a secure hold of the bar 51 in either locking or releasing position.

Various minor details of construction will be apparent from the drawings. The shaft 15 10 is mounted in bearings 30 on suitable cross bars 13, the tamper bars 15 may be guided in slots 35 and 36 of bars 13. The lower ends of the bars 14 are fixed to the front ends of suitable frame bars that are 20 mounted for slight pivotal movement in a vertical plane, so that by the provision of nuts 55 on said bars 14 bearing against a fixed part the bars may be adjusted up and down in the frame. Since the shafts 40 25 are pivoted in bars 14, vertical adjustment of the latter will determine how high the locking bar 51 may raise the tamper bars. These nuts are preferably adjusted so that when the tamper bars are at their extreme 30 upper position, the bar 29 may swing in with positive clearance of the edges 33; and yet when the tampers are unlocked, they will permit the bar 51 to enter beneath the forward end of the edges 34 just as the bar 29 35 is leaving edges 33. Further throw of the parts 39, 42, 44 and 51 will then raise the tampers, to position blocks 31 out of reach of the bar 29.

Operation: Assuming that the parts are in 40 position as shown in Fig. 4, that the power shaft 10 is rotating continuously, that suitable material is provided beneath the tamper feet 54, and that it is desired to apply pressure or crushing force to said material; as 45 the shaft 10 is rotated by pulley 11, bar 29 strikes the edges 13 of the several blocks 31, since the shaft is rotating in a clockwise direction as shown in such view, raising all the tampers together to the position shown 50 in Fig. 3, after which the said bar 29 slides out from under the blocks which with the tampers 15 thereupon fall together, so that the feet 54 strike the material to be operated upon. This operation continues, the tampers 55 rising and falling at each rotation of the shaft, as long as the power shaft revolves and the locking mechanism is not set to obstruct the falling of the tampers.

When it is desired to lock the tampers in 60 inactive position, the lever arm 39 is moved manually forward from its position in Figs. 3 and 4 to that in Fig. 2. Such movement does not positively force the arms 44 and 64 with bar 51 rearwardly, but does release the 65 same, which are loosely pivoted upon the

bar 38, so that spring 53 may draw them towards the tampers without exerting a positive jarring action upon the lever 39 which might be injurious to the operative's arm. When the bar 51 approaches the tampers, 70 if the blocks 31 are up and the forward ends of the edges 34 are high enough to permit the said bar to enter under the same, the bar will finally take a position as shown in Fig. 3 of the drawings, when a further 75 forward thrust of the lever 39 will positively rock the bar 38 with the parts 42 acting as cranks about the shafts 40, as fulcra, and thereby force arms 44 and 64 upwardly, the spring 53 meanwhile causing the bar 51 80 to cling to the forward edges of the tampers, and lift the blocks 31 still higher to the extreme position as shown in Fig. 2. There they will remain until the lever 39 is thrust rearwardly to lower the arms and thereby 85 lift the blocks when they will be brought again within the reach of the rotating bar 29, and the pounding action of the tampers then resumed.

It will be noted that spring 50 connects 90 movable parts, while spring 53 connects the movable arm 44 with a fixed part of the frame. The lever 49 controls lug 41 positively and directly while arm 43 is controlled by the lug 41 within certain limits 95 but has a large idle motion within the limits of the latter. The actuation of lever 39 will therefore control 43 and by the latter exerting a pulling force on 44, will finally overcome the force of spring 53 as above stated. 100

Another valuable result is attained by our structure arising from the fact that the parts 40, 38 and 51 are almost in alinement 105 in their relative position as shown in Fig. 2, and parts 40, 38 and 43 in substantial alinement in Figs. 3 and 4. First, when the tamper bars are locked in the highest position as shown in Fig. 2, the parts are in a substantially neutral position. While it is true that the fulcrum 38 of the parts 42, 110 and 44 (referring now to one side only of the machine as shown in Fig. 2), is slightly out of alinement with 51 and 40, the force exerted by spring 53, tends sufficiently to counteract the force which the weight of 115 the tampers on the bar 51 exerts, since 47, 51 and 52 are not quite in alinement, and as a result, the lever 39 is approximately neutral; and second when the bar 51 is withdrawn to the position shown in Fig. 4, the 120 force of the spring 53 (tending to urge bar 51 towards the tamper bars) is partly neutralized by the weight of the parts 38, 41, 42, 43 and 44, since all may be considered 125 as swinging upon the pivot 40, and therefore a substantially neutral position exists in the unlocked relation of the lever. From these arrangements easy manipulation of the locking mechanism is effected which would not otherwise be practicable. 130

Although these conditions exist as above stated, notches 57 are provided in the bar 56 to receive the lever 39 therein to positively hold the latter in either extreme position.

5 While the tamper bars may be guided in slots in the frame, other guiding means may be provided, as desired. The belt pulley 11 may be mounted upon either end of the shaft 10, as may be most convenient. Also, 10 the levers 42 may be integral with 40, the latter swinging in apertures in the frame bars 14; or the parts 40 could evidently be made integral with a frame part and the levers 42 provided with sleeves on their 15 lower ends, pivoted on 40, it being only essential that the lever 39 and lug 41 shall positively operate one of the levers 42. All these are matters of detail only, and it is understood that minor changes may be 20 made without departing from the spirit and scope of our invention as claimed.

What we claim as new and desire to secure by United States Letters Patent is:

1. A tamping machine comprising a 25 frame, tamping bars mounted for vertical reciprocation in said frame, transverse blocks fixed upon the respective tamper bars having their ends projecting forwardly and rearwardly thereof, means for contacting 30 said blocks and thereby intermittently raising the tamper bars and releasing them to permit the latter to fall by gravity, a transverse bar mounted in said frame for swinging movement toward and from said tamper 35 bars and slidably vertically, so that its extreme upward throw will contact said blocks and lift them beyond the reach of said raising means, and whose outwardly swung position will be out of reach of the said blocks as the tampers rise and fall and manually-actuated means for actuating said transverse bar.

2. A tamping machine comprising a supporting frame, tamping bars reciprocably 45 mounted therein, a power shaft journalled transversely thereof, transverse members mounted in parallelism on said shaft and having offset portions thereon, arms pivoted on said members, the arms and said portions 50 having perforations in alignment in certain positions of said arms, bolts secured on said arms and portions for movement therethrough, compression springs between said arms and perforations, and other springs 55 secured between the external surface of said portions and the ends of the bolts, a transverse bar carried by said arms parallel to said shaft, and transverse blocks fixed upon the respective tamper bars and normally in 60 the path of transit of said transverse bar about the shaft, whereby the rotation of said shaft will intermittently raise the several tamper bars and release them to permit them to fall by gravity.

3. A tamping machine comprising a

frame, tamping bars mounted side by side for vertical reciprocation in said frame, transverse blocks fixed upon the respective tamper bars and having their ends projecting forwardly and rearwardly thereof, means 70 rearwardly of said tamper bars for contacting the rear ends of said blocks and thereby intermittently raising and releasing the tamper bars to permit the latter to fall by gravity, a transverse bar mounted in said 75 frame forwardly of the tamper bars for swinging movement toward and from said tamper bars and slidably vertically, so that its extreme upward throw will contact the forward ends of said blocks and lift them beyond the reach of said raising means, and whose outwardly swung position will be out of reach of the said blocks as the tampers 80 rise and fall, and manually-actuated means for actuating said transverse bar. 85

4. A tamping machine comprising a frame, tamping bars mounted for vertical reciprocation in said frame, a power shaft journalled upon and transversely of said frame, means for rotating said shaft, transverse blocks fixed upon the respective tamper bars having ends projecting forwardly and rearwardly thereof, means rotating with said shaft and eccentrically thereof for contacting said blocks at each rotation to intermittently raise the several tamper bars and release them to permit the latter to fall by gravity, a transverse bar mounted in said frame for swinging movement toward and from said bars and slidably vertically, so that its extreme upward throw will contact said blocks and lift them beyond the reach of said raising means, and whose outwardly swung position will be out of reach of the said blocks as the tampers rise and fall, and manually-actuated means for actuating said transverse bar. 95

5. A tamping machine comprising a supporting frame, tamping bars mounted to vertically reciprocate in said frame, a power shaft journalled transverse of said frame, eccentric support-means carried by said shaft and rotating therewith, a pair of members pivoted upon said supporting means, a bar connecting said members and parallel with said shaft, said members being movable toward and away from other portions of said supporting means, compression springs guided between said pivoted member and said portions, transverse blocks fixed upon the respective tamper bars and projecting forwardly and rearwardly thereof, the forward ends being normally in the path of transit of said transverse bar about the shaft, whereby the rotation of the latter will intermittently raise the several tamper bars and release them to permit their falling by gravity, and manually-actuated means on the side of said tampers opposite from said transverse bar for temporarily rendering the 100 110 115 120 125 130

lifting action of said bar ineffective though the power shaft rotate continuously.

6. A tamping machine comprising a supporting frame, tamping bars mounted to reciprocate vertically in said frame, a power shaft journalled transverse of said frame, transverse plates mounted on said shaft in parallelism and having offset portions thereon, pivoted arms fulcrumed on said plates and adapted to rock toward and away from said portions, the latter and said arms having perforations which are in alinement in certain positions of said arms, bolts inserted through said alined perforations and having heads outside of said arms and projecting below said offset portions, coiled compression springs encircling said bolts between said arm and portions, discs secured on said bolt ends by cotter-pins and spaced from said portions, coil springs on said bolt ends between said portions and said discs, a transverse bar carried by said arms parallel with said shaft, and transverse blocks fixed upon the respective tamper bars and normally in the path of transit of said transverse bar about the shaft, whereby the rotation of said shaft will intermittently raise the several tamper bars and release them to permit them to fall by gravity.

30 7. A tamping machine comprising a frame, tamping bars mounted to vertically reciprocate in said frame, a power shaft journalled transverse upon said frame, a transverse bar carried eccentrically upon and parallel to said shaft but yieldingly thereto, transverse blocks fixed upon the respective tamper bars and normally in the path of transit of said transverse bar about the shaft, whereby the rotation of said shaft will intermittently raise the several tamper bars and release them to permit them to fall by gravity, and manually-actuated means on the opposite side of said tamper bars from said transverse bar for temporarily rendering the lifting action of said bar ineffective, though the shaft rotate continuously.

8. A tamping machine comprising a frame, tamping bars mounted to vertically reciprocate in said frame, a power shaft journalled transverse upon said frame, eccentric supporting means carried by said shaft and rotating therewith, a pair of members pivoted upon said supporting means in a line parallel with said shaft and movable toward and away from other portions of said supporting means, compression springs guided between said pivoted members and said portions, a transverse bar carried by said supporting means parallel to said shaft, and transverse blocks fixed upon the respective tamper bars and normally in the path of transit of said transverse bar about the shaft, whereby the rotation of said shaft will intermittently raise

the several tamper bars and release them to permit them to fall by gravity.

9. A tamping machine comprising a frame, tamper bars mounted for vertical reciprocation in said frame, transverse blocks fixed upon the respective tamper bars having their ends projecting forwardly and rearwardly thereof, means for contacting said blocks and thereby intermittently raising the tamper bars, and releasing them to permit the latter to fall by gravity, a transverse bar mounted for swinging movement in said frame toward and from the tamper bars and parallel with the power shaft, means to actuate said transverse bar to rock into contact with said tamper bars and under said blocks, and subsequently to lift the blocks and tampers vertically out of reach of said intermittent raising means.

10. A tamping machine comprising a supporting frame, tamper bars mounted in said frame for reciprocation in substantially the same plane, means for actuating said tamping bars intermittently, and means for temporarily holding the latter in raised position, including blocks fixed on the several bars and projecting therefrom, a pair of vertical frame bars suspended from the upper parts of the frame at its ends, and means for adjusting the longitudinal position of said frame bars, locking means pivoted upon said adjustable bars for rocking forwardly and rearwardly thereof towards and from said tamper bars, for engaging the lower edges of said blocks to retain the same and their tamper bars in raised position, and manually-operated means for actuating said locking means.

11. A tamping machine comprising a supporting frame, tamper bars mounted in said frame for reciprocation in substantially the same plane, means for actuating said tamping bars intermittently, and means for temporarily holding the latter in raised position, including blocks fixed on the several bars and projecting forwardly thereof, a crank mechanism mounted in said frame for rocking motion toward and from said tamper bars, a transverse bar mounted eccentrically on said crank mechanism for engaging said blocks and preventing their descent, a pair of extension springs connected with said transverse bar, one extending rearwardly and connected to a frame part and tending normally to urge said transverse bar towards said tamper bars, and the other extending forwardly and opposing said first spring but exerting a greater force than the first, a rock arm pivoted in said crank mechanism transversely of said bar, said crank mechanism having means for controlling said rock arm within certain limits, the forwardly extending spring being connected to the end of said rock arm and manually operated

means for actuating said crank mechanism.

12. A tamping machine comprising a supporting frame, tamper bars mounted for vertical reciprocation in said frame, a power shaft journalled upon and transversely of said frame, means for rotating said shaft, transverse blocks fixed upon the respective tamper bars and having ends projecting forwardly and rearwardly thereof, means ro-

10 tating with said shaft and eccentrically thereof for contacting said blocks at each rotation to intermittently raise the several tamper bars and release them to permit the latter to fall by gravity, means for lifting 15 said tamper bars beyond the reach of said intermittently raising means, including a rock shaft journalled transverse of said frame for movement toward and from said tamper bars, arms loosely pivoted on said

20 rock shaft, a transverse bar mounted on the ends of said pivoted arms and adapted to engage the lower edges of said blocks, spring means for urging said bar toward said tamping bars, and manually operated means 25 for actuating said rock shaft.

13. A tamping machine comprising a supporting frame, tamper bars mounted for vertical reciprocation in said frame, a power shaft journalled upon and transversely of 30 said frame, means for rotating said shaft, transverse blocks fixed upon the respective tamper bars and having ends projecting forwardly and rearwardly thereof, means rotat-

35 ing with said shaft and eccentrically thereof for contacting said blocks at each rotation to intermittently raise the several tamper bars and release them to permit the latter to fall by gravity, means for lifting said tamper bars beyond the reach of said

40 intermittently actuating means, including a rock shaft journalled transverse of said frame for movement toward and from said tamper bars, arms loosely pivoted on said rock shaft, a transverse bar mounted on the

45 ends of said pivoted arms and adapted to engage the lower edges of said blocks, spring means for urging said bar toward said tamping bars, a rocking arm pivoted upon said rock shaft, yielding means connected with said rocking arm for controlling said spring means, and manually-operated means for actuating said rock shaft and controlling said rock arm on its pivot.

14. A tamping machine comprising a supporting frame, tamping bars mounted for vertical reciprocation in said frame, means for intermittently raising said bars and releasing them to permit their fall by gravity, means for lifting said tamper bars beyond

55 the reach of said intermittent actuating means including blocks on said bars projecting forwardly thereof, a rock shaft journalled eccentrically transverse of said frame for movement toward and from said tamper bars, arms loosely pivoted on said rock shaft,

a transverse bar mounted on the ends of said pivoted arms and adapted to engage the lower edges of said blocks, one of said pivoted arms having a pair of extensible springs connected therewith, one of said springs extending rearwardly and connected to a frame part and tending to normally urge said bar toward said tamping bars, and the other extending forwardly and opposing said first spring but exerting a greater force than the first, a rock arm pivoted upon said rock shaft, means keyed to the latter for controlling said rock arm within certain limits, the forwardly extending spring being connected to the end of said rock arm and manually operated means for actuating said rock shaft.

15. A tamping machine comprising a supporting frame, tamper bars mounted in said frame for reciprocation in substantially the same plane, means for actuating said tamper bars, and means for temporarily holding the latter in raised position including blocks fixed on the several bars and projecting forwardly thereof, a rock shaft journalled ec-

centrically transverse of said frame for movement toward and from said tamper bars, arms of unequal length loosely pivoted on said rock shaft, a transverse bar mounted on the end of the shorter arm and on the mid-length of the longer, and adapted to engage the lower edges of said blocks, the end of the longer arm having a pair of extension springs connected therewith, one extending from a point thereof spaced from its end, rearwardly and connected to a frame part and tending to normally urge said bar toward said tamping bars, and the other extending forwardly from its extreme end and opposing the first, a rock arm pivoted upon said rock shaft at its end adjacent the longer of said arms, means keyed to the latter for controlling said rock arm within certain limits, the forwardly extending spring being connected to the end of said rock arm, and manually operated means for actuating said rock shaft.

16. A tamping machine comprising a frame, tamper bars mounted for vertical reciprocation in said frame, transverse blocks fixed upon the respective tamper bars having their ends projecting forwardly and rearwardly thereof, means for contacting the rear ends of said blocks and thereby in-

termittently raising the tamper bars and releasing them to permit the latter to fall by gravity, a transverse bar mounted for swinging movement in said frame toward and from the tamper bars and in parallelism with the power shaft means to actuate said transverse bar to rock into contact with said tamper bars and under the forward ends of said blocks, the said transverse bar being also movable vertically, and means for actuating said transverse bar to hold the said

tamper bars in their raised position by engaging their said blocks, and subsequently to lift the blocks and tampers vertically out of reach of said intermittent raising means.

5 17. A tamping machine comprising a supporting frame, tamper bars mounted in said frame for reciprocation in substantially the same plane, means for actuating said tamper bars intermittently to move 10 them in one direction, and means for temporarily holding them in said moved position, including blocks fixed on the several bars and projecting therefrom, a pair of vertical frame bars suspended from the upper parts of the ends of the frame, screw means in threaded connection with said suspended bars and in contact with frame parts for adjusting the longitudinal position of said suspended bars, locking means pivoted 15 upon said adjustable bars for rocking thereon forwardly and rearwardly toward and from said tamper bars for engaging said blocks in its position adjacent the latter to retain the same and their tamper bars in 20 a common longitudinal position, spring means tending to rock said pivoted locking means toward the tamper bars, and manually-operated means for actuating said locking means to move the blocks and tamper bars in a direction longitudinal of the latter. 25

18. Mechanism for raising and holding in raised position a series of elongated bars movable in a common plane and having transverse blocks fixed upon each of said bars and having their ends projecting from the bars, comprising a supporting frame, a crank mechanism mounted in said frame for rocking motion toward and from said bars, a transverse bar mounted eccentrically on said crank mechanism for rocking motion thereon for engaging in its rearmost throw the lower edges of said blocks and preventing their descent, yielding means for urging said transverse bar towards said series of bars, a rock arm pivoted on said crank mechanism in a plane transverse of said transverse bar, means for positively actuating said crank mechanism and for limiting the movement of said rock arm on its pivot, spring means for connecting said rock arm and said transverse bar tending to withdraw said transverse bar from said series of bars, a manually-operated lever for actuating said crank actuating means, the said rock arm, transverse bar and spring means being so mounted relatively to each other that the said manual lever will be in neutral position both when the transverse bar is 50 in its locking position and when in its withdrawn or idle position.

19. Mechanism for raising and holding in their raised position a series of elongated bars movable in a common plane and having transverse blocks fixed upon each of

said bars with their ends projecting therefrom, comprising a supporting frame, a crank mechanism mounted in said frame for rocking motion toward and from said bars, a transverse bar mounted eccentrically on said crank mechanism for rocking motion thereon for engaging in its rearmost throw the lower edges of said blocks and preventing their descent, a pair of extension springs connected with said transverse bar and extending in opposite directions therefrom to counteract each other, and one of them being connected to a frame part, a rock arm pivoted in said crank mechanism transversely of said transverse bar and 75 said crank mechanism having means for controlling the movement of said rock arm within certain limits, the other spring being connected to said rock arm and exerting a greater force than the first, the frame-connected spring tending to normally urge said transverse bar towards the said series of bars, and manually-operated means for actuating said crank mechanism to release the said rock arm and thereby the stronger 80 spring whereby the said transverse bar contacts the series of bars, and thereafter lifts said transverse bar and therewith said blocks and connected parts to a higher 85 position. 90

20. A tamping machine comprising a supporting frame, tamper bars mounted in said frame for reciprocation in substantially the same plane, means for actuating said tamper bars, and means for temporarily holding the latter in raised position, including blocks fixed on the several bars and projecting forwardly thereof, a rock shaft journalled eccentrically transverse of said frame for movement toward and from said tamper bars, arms loosely pivoted on said rock shaft, a transverse bar mounted on the ends of said pivoted arms and adapted to engage the forward edges of said tamper bars and the lower edges of said blocks, one 100 of said pivoted arms having a pair of extension springs connected therewith, one extending rearwardly and connected to a frame part, and the other extending forwardly and opposing the first, a rock arm 105 pivoted upon said rock shaft adjacent the pivoted arm having spring connections, a manually-operated lever for actuating said rock shaft, a lug integral with said lever and having an open face limited in lateral 110 extent by projecting shoulders between which said pivoted rock arm may move upon the rock shaft within certain limits, the forwardly-extending spring being connected to the end of said rock arm, and a frame 115 bar having notches therein for positively locking said lever in either of its extreme positions. 120

21. A tamping machine comprising a supporting frame, tamper bars mounted for 130

vertical reciprocation in said frame, a power shaft journalled upon and transversely of said frame, means for rotating said shaft, transverse blocks fixed upon the respective tamper bars and having ends projecting forwardly and rearwardly thereof; means rotating with said shaft and eccentrically thereof for contacting the rear ends of said blocks at each rotation to intermittently raise the several tamper bars and release them to permit the latter to fall by gravity, means for preventing temporarily the descent of said tamper bars, including a rock shaft journalled transverse of said frame for movement toward and from said tamper bars, arms loosely pivoted on said rock shaft, a transverse bar mounted on the ends of said pivoted arms and

adapted to engage the lower edges of said blocks to retain the latter and their tamper bars at the height to which said eccentrically-rotating means may raise them, spring means for urging said transverse bar into contact with the forward edges of said tamper bars, and manually-operated means for actuating said rock shaft and thereby said loosely-pivoted arms to lift the said transverse bar and with it said blocks and tamper bars, to a position above the highest point and positively out of reach of said eccentrically-mounted rotating means.

In testimony whereof we hereunto affix our signatures.
